UNITED STATES PATENT OFFICE.

JOHN A. LAMONT AND CARL M. STENBERG, OF CHICAGO, ILLINOIS, ASSIGNORS TO AMERICAN STEEL FOUNDRIES, OF CHICAGO, ILLINOIS, A CORPORATION OF NEW JERSEY.

SIX-WHEEL EQUALIZING TRUCK.

Application filed April 30, 1921. Serial No. 465,941.

To all whom it may concern:

Be it known that we, JOHN A. LAMONT and CARL M. STENBERG, citizens of the United States, residing at Chicago, in the 5 county of Cook and State of Illinois, have invented certain new and useful Improvements in Six-Wheel Equalizing Trucks of which the following is a specification.

This invention relates to railway car 10 trucks, and more particularly to load equalizing mechanism for six-wheel trucks.

One object of the invention is to simplify and improve load equalizing mechanism for railway car trucks and to reduce the 15 number of parts and improve the cooperative action therebetween.

Another object is to provide load equalizing mechanism for six-wheel trucks adapted to meet the various requirements for successful commercial operation.

These and other objects are accomplished by means of the arrangement disclosed on the accompanying sheet of drawings, in which—

25 Figure 1 is a fragmentary vertical longitudinal sectional view of a six-wheel truck embodying my invention, parts of the equalizing mechanism being shown in side elevation;

30 Figure 2 is a fragmentary horizontal longitudinal sectional view of the same;

Figure 3 is a half sectional view taken in the plane of line 3—3 of Figure 1, the right-hand half of the side frame and its 35 associated parts only being shown; and

Figure 4 is a fragmentary sectional view taken in the planes of the irregular line 4—4 of Figure 1.

The various novel features of the invention will be apparent from the following description and drawings and will be particularly pointed out in the appended claims.

The invention is disclosed in connection with a six-wheel truck including an integrally formed side frame 10 having two end pockets (not shown) for end journal boxes, and an intermediate pocket 11 for a middle journal box 12. In this particular instance the journal box is provided with 45 upwardly and outwardly extending spaced side walls 13 joined at their outer ends by ends walls 14 which slidably engage ver-

tical guide walls 15 or wear plates 16 connected thereto for guiding the associated journal box in its relative vertical movements with respect to the side frame. 55

The main body portion of the journal box 12 includes a top 17 having a concave portion 18 for the reception of a rocker portion 19 of an equalizing beam 20 upon which are mounted a plurality of springs 21 for yieldably transmitting loads through said beam 20 to the journal box 12. Mounted upon the springs is a spring cap in the form of a yoke or inverted U-shaped member 22 60 having depending arms 23 which extend downwardly through spaces between the side walls 13 and the end walls 14 and the main portion of the journal box 12. The lower ends of the arms 23 are bifurcated and receive therebetween the inner ends of equalizing levers 24, said inner ends of said levers having recessed portions resting upon and receiving pins 25 extending through aligned openings in the bifurcated or lower 65 ends of the arms 23. The outer end of each of these equalizing levers terminates in an upwardly extending portion which passes upwardly between side walls 26 of the side frame 10, each outer end of said levers having opening 27 for the reception of a rocker member or pin 28, the lower surface of which is convex and is rockably supported upon a horizontal floor 29 formed by aligned openings 30 in the side frame walls 26. By 70 thus having the outer ends of equalizing levers 24 mounted on rockers 28, the equalizing mechanism is permitted to move longitudinally with respect to the truck incident to starting and stopping actions of the car 75

for the purpose of preventing the equalizing mechanism as such from taking shocks resulting from such starting and stopping actions. These shocks are taken by and between the transverse bolster members 32 which are rockably mounted upon intermediate portions of equalizing levers 24, and by side walls 31 of the pockets which receive the bolster members 32. When the equalizing levers 24 move longitudinally prior to the time that the bolster members 32 engage the pocket side walls 31, not only will the members 28 rock but also the yoke 22 will be given a rocking motion through 80 85 90 95 100

its arm 23, which rocking motion in turn will be transmitted through the springs 21 to the equalizing beam 20 which will rock on the top 17 of the intermediate journal 5 box 12.

Also the equalizing beam will be caused to rock on its support in accordance with load equalizing conditions, it being understood that the loads are transmitted through 10 the bolster members 32, equalizing levers 24, spring cap or yoke member 22, springs 21, and equalizing beam 20 to the journal box 12. Under certain conditions there is a tendency for the arms 23 to spread and to 15 prevent this the pins 25 are formed integrally with a connecting bar 33 which passes under the lower curved portion of the journal box 12.

It is our intention to cover all modifications of the invention falling within the spirit and scope of the following claims.

We claim:

1. In a six-wheel car truck, the combination of an intermediate journal box, an 25 equalizing beam rockably mounted on said box, resilient means mounted on said beam, and means including a member capping said resilient means for transmitting a load through said resilient means and beams to 30 said box.

2. In a railway car truck, the combination of a support, an equalizing beam rockably mounted on said support, resilient means mounted on said beam, and means including 35 a member capping said resilient means for transmitting a load through said resilient means and beam to said support.

3. In a six-wheel car truck, the combination of an intermediate journal box, an 40 equalizing beam movably mounted on said box, resilient means mounted on said beam, a cap mounted over said springs, and equalizing levers operatively connected to said cap for transmitting loads therethrough and 45 through said resilient means and equalizing beam to said journal box.

4. In a six-wheel car truck, the combination of an intermediate journal box, an equalizing beam movably mounted on said 50 box, resilient means mounted on said beam, a cap mounted over said springs, equalizing levers operatively connected to said cap for transmitting loads therethrough and through said resilient means and equalizing beam to 55 said journal box, and means for rockably

supporting the outer ends of said equalizing levers to permit longitudinal movement of same to prevent said equalizing parts from taking shocks incident to starting and stopping of the car.

5. In a six-wheel car truck, the combination of an intermediate journal box, equalizing mechanism operatively connected thereto and including a load carrying member rockably mounted with respect to said journal 60 box and also including an equalizing lever the relatively fixed end of which is rockably supported whereby the equalizing mechanism is permitted to move longitudinally of the truck incident to starting and stopping 65 of the car to prevent said equalizing mechanism from taking shocks incident to said starting and stopping actions.

6. In a six-wheel truck, the combination of an intermediate journal box, equalizing 70 levers operatively connected thereto for transmitting loads to said box, and rockers at the outer ends of said equalizing levers for permitting the latter to move longitudinally of the truck upon starting and stopping 75 of the truck to prevent such equalizing mechanism from taking shocks incident to said starting and stopping actions.

7. In a six-wheel truck, the combination of a journal box having outwardly extending 80 spaced walls, a spring cap for transmitting loads toward said journal box and having arms extending between said spaced walls of said journal box, and equalizing levers operatively connected to said arms.

8. In a six-wheel truck, the combination of an intermediate journal box, equalizing levers, a spring cap having depending arms to which loads are transmitted from said 85 equalizing levers toward said journal box, and pins forming the connection between said equalizing levers and arms and being connected by an intermediate connecting portion to prevent said arms from assuming 90 relatively abnormal positions.

9. In a six-wheel car truck, the combination of an intermediate journal box, an equalizing member movably mounted on said box, springs mounted on said member, a cap mounted over said springs, and equalizing 100 levers operatively connected to said cap.

Signed at Chicago, Illinois, this 18th day of April, 1921.

JOHN A. LAMONT.
CARL M. STENBERG.
